[57] CLAIM

The ornamental design for front display panel for vending machines, substantially as shown and described.

DESCRIPTION

FIG. 1 is a front elevational view of a front display panel for vending machines showing our new design;

FIG. 2 is a rear elevational view thereof;

FIG. 3 is a top plan view thereof, the bottom being identical thereto;

FIG. 4 is a left end elevational view thereof, the right end being a mirror image thereto;

FIG. 5 is an enlarged sectional view as taken from line 5—5 of FIG. 6;

FIG. 6 is an enlarged fragmentary front elevational view thereof.
